CLAIM

The ornamental design for a container system, as shown and described.

DESCRIPTION

FIG. 1 is an upper perspective view of an embodiment of a container system;

FIG. 2 is an upper perspective view of a container of the container system shown in FIG. 1;

FIG. 3 is a lower perspective view of the container of the container system shown in FIG. 2;

FIG. 4 is a front view of the container of the container system shown in FIG. 2;

FIG. 5 is a rear view of the container of the container system shown in FIG. 2;

FIG. 6 is a left side view of the container of the container system shown in FIG. 2;

FIG. 7 is a right side view of the container of the container system shown in FIG. 2;

FIG. 8 is a top view of the container of the container system shown in FIG. 2;

FIG. 9 is a bottom view of the container of the container system shown in FIG. 2;

FIG. 10 is an exploded, upper perspective view of the container system shown in FIG. 1;

FIG. 11 is an exploded, lower perspective view of the container system shown in FIG. 1;

FIG. 12 is an upper perspective view of another embodiment of a container system;

FIG. 13 is an upper perspective view of a container of the container system shown in FIG. 12;

FIG. 14 is a lower perspective view of the container of the container system shown in FIG. 13;

FIG. 15 is a front view of the container of the container system shown in FIG. 13;

FIG. 16 is a rear view of the container of the container system shown in FIG. 13;

FIG. 17 is a left side view of the container of the container system shown in FIG. 13;

FIG. 18 is a right side view of the container of the container system shown in FIG. 13;

FIG. 19 is a top view of the container of the container system shown in FIG. 13;

FIG. 20 is a bottom view of the container of the container system shown in FIG. 13;

FIG. 21 is an exploded, upper perspective view of the container system shown in FIG. 12; and,
